[57] **CLAIM**

The ornamental design for a dispenser closure, as shown.

DESCRIPTION

FIG. 1 is a top perspective view of a dispenser closure in open position showing my new design, the container shown in broken lines for illustrative purposes only; FIG. 2 is a side elevation thereof, the opposite side being identical;

FIG. 3 is a top plan view thereof, in open position;

FIG. 4 is a top plan view thereof, in closed position.

FIG. 1

FIG. 3

FIG. 4

FIG. 2
